UNITED STATES PATENT OFFICE.

FREDERIC G. HODELL, OF CLEVELAND, OHIO.

CHAIN PUMP-BUCKET.

No. 872,423.

Specification of Letters Patent.

Patented Dec. 3, 1907

Application filed June 24, 1907. Serial No. 380,378.

To all whom it may concern:

Be it known that I, FREDERIC G. HODELL, a citizen of the United States, residing at Cleveland, in the county of Cuyahoga and State of Ohio, have invented certain new and useful Improvements in Chain Pump-Buckets, and do declare that the following is a full, clear, and exact description of the invention, which will enable others skilled in the art to 10 which it appertains to make and use the same.

My invention relates to improvements in chain pump buckets, and the invention consists in a pump bucket having cores or link 15 members in single pieces with rubber buckets removably and adjustably mounted thereon, whereby each complete joint or link of the chain is constituted of two parts only and an exceedingly simple and efficient construction. 20 is afforded having all needed range of adaptability, all substantially as shown and described and particularly pointed in the claims.

In the accompanying drawings Figure 1 is 25 an elevation of the invention with the bucket in section and in normal position on the core. Fig. 2 shows a sectional elevation of both bucket and core with the bucket adjusted to a spreading position. Fig. 3 is a sectional 30 elevation of the bucket alone and Fig. 4 is a sectional elevation of a modification of the core.

Mechanically, the invention consists of only two parts, the metallic core or link A, 35 and the rubber bucket or bell shaped member B. Said core or link has the usual eyes 2 at its ends for connection with the other cores or links of the chain, and is cast with an externally threaded shank 3 and disk 4 next 40 to said shank. Said disk, preferably, has a beveled or equivalently formed edge 5. That is, the edge is preferably beveled or tapered transversely from its widest portion *x* next to said shank 3 to its narrowest portion *y* 45 below, while the bucket is substantially bell shape and has an internally threaded neck 6 screwed directly onto shank 3 from above, and an internal annular channel or recess 7 providing a spreading lip 10 adapted to engage 50 about the edge of disk 4 and to spread laterally as the bucket is adjusted upward

more or less by rotation on thread 3 and the edge 8 of the bucket rises about the edge of disk 4 and forces the lower edge of the bucket outward correspondingly. It is to be noticed 55 that said lower edge is deepest in cross section by reason of the incline of bevel 8 inward higher up, so that as the bucket is bodily moved upward this wider portion of its edge readily compensates for any looseness or 60 wear that may have come on the parts. Such adjustment is shown in full lines, Fig. 2. This construction also makes it convenient to remove and replace a defective bucket and especial novelty is believed to reside in the 65 core itself in that it is cast bodily in one piece with threaded shank and disk and no machine work of any kind is required to prepare the core to receive the disk or the bucket. 70

Fig. 4 shows a modification of disk in that the disk 9 shown herein has not a beveled edge 5, as in the other views, but is merely round across its edge. The bucket shown will work with this style of disk also, but the 75 former construction is preferred because a flat bearing surface 5 on the edge of the disk affords a broader and better backing for the bucket.

What I claim is:—

1. In chain pump buckets, a metallic core having a threaded shank and a fixed disk at the base of the shank, in combination with a flexible bucket adjustably screwed on said shank and having an inner annular bevel at 85 its edge engaged beneath the edge of said disk.

2. In chain pump buckets, a metallic core having a threaded shank and a fixed beveled disk integral therewith, in combination with 90 a substantially bell shaped bucket threaded on said shank and having its widest portion engaged about said disk, said widest portion having an internal annular channel provided with a beveled surface at its bottom portion 95 adapted to match the beveled edge on said disk, whereby the said bucket may be spread to take up wear, substantially as herein set forth.

3. In chain pump buckets, an integral core 100 member having a threaded shank and an annular spreading disk at the base of said shank

- provided with a beveled outer edge —5—, in combination with an expansible bucket having an interiorly threaded neck engaged on said shank and an enlarged body portion
- 5 provided with an annular spreading lip at its bottom and an inner beveled edge adapted to bear against said beveled edge —5— and thereby spread the said enlarged body por-

tion of the bucket to make a close working fit of the parts.

In testimony whereof I sign this specification in the presence of two witnesses.

FREDERIC G. HODELL.
